WATCH HOLDER

Max E. Westerman, New York, N. Y.

Application December 19, 1935, Serial No. 55,135

7 Claims. (Cl. 58—105)

The present invention relates to watch holders of the type in which the holder forms a peripheral flange upon the watch case, extending in the plane of the case.

5 The holder is preferably made of leather or similar somewhat resilient and flexible material, having an opening therethrough to receive the watch. The watch has a cylindrical case with a flange at each end of the cylinder, at least one 10 of which flanges is adjustable toward the other, so that the holder may be firmly clamped between them.

Obviously the holder must be normally slightly thicker than the cylindrical body of the case so 15 that when clamped between the flanges it will be compressed and tightly gripped.

While leather that is stiff enough for use in such holders is compressible, its compressibility is not sufficient to provide a wide tolerance and the normal thickness of the leather must be kept within 20 comparatively close limits. The adjustable flange is usually formed on the rear face plate of the case which is screwed into the cylindrical body. If the holder is too thick it will be impossible to 25 screw this plate home tightly against the cylinder. On the other hand, if the holder is too thin it will be loose on the case and unsatisfactory for that reason.

Unfortunately leather is not a material that 30 can, as a matter of commercial expediency, be held to an accurate gauge of thickness. Even though they may be cut from the same piece of leather, the holders may vary in thickness considerably beyond permissible limits. Such wide 35 variations involve waste of material and waste of time and labor in fitting the holders to the cases. In addition to this, the cases may also vary in thickness thus adding to the manufacturing difficulties.

40 An object of the present invention is to overcome these difficulties by providing a holder of leather or like material which at least along the margin of the watch case opening, will be considerably more resiliently compressible than is 45 ordinary solid leather.

A more specific object is to provide a holder formed of laminae that are normally sprung apart at the periphery of the opening. Thus the holder will fit snugly between flanges that may vary considerably in spacing. Also, considerable variations in thickness of the leather may be tolerated without affecting the fit of the holder.

With these objects in view and others which 55 will appear hereinafter I shall now describe a preferred embodiment of my invention and will

thereafter point out the novelty and scope of the invention in the claims.

In the accompanying drawing:

Figure 1 is a view in perspective of a watch fitted with my improved holder; 5

Fig. 2 is a view in section taken on the line 2—2 of Figure 1;

Fig. 3 is a face view of the holder with the watch removed; and

Fig. 4 is a fragmental view of the holder in 10 transverse section showing the normal flare of the laminae at the margin of the watch case opening.

The holder comprises a piece 10 of leather or other similar material. The holder illustrated is in the form of a ring, but obviously the outer periphery need not necessarily be circular, but may be oval, rectangular, or of any other desired contour. The inner periphery 11 of the holder is formed to fit closely upon the cylindrical case 12 of the watch 13. A notch 14 is formed in the 20 inner periphery of the holder to clear the crown 15 of the watch. It will be noted that this crown is of a diameter greater than the thickness of the holder so that the crown will protrude slightly from opposite faces of the holder. Hence the 25 watch may be wound or set without removing it from the holder.

The watch case has a flange 16 which laps over the edge of the holder on one face thereof and a flange plate 17 is screwed or otherwise secured to 30 the case so that it will lap over the edge of the holder on the opposite face thereof. Thus the watch is held firmly in place within the holder since the latter is gripped snugly between the flanges 16 and 17. To increase the compressibility 35 of the holder along its inner periphery it is slit, as indicated at 18, and a cord 19 is tightly wedged in the slit to flare apart the lips or laminae between which the slit is formed. While the holder may be made of a single solid piece of leather with a 40 slit formed therein I prefer to make it of two laminae 20 and 21, which are stitched together as indicated at 22 adjacent their outer periphery.

When the holder is fitted upon the watch and clamped between the flanges, the opposite faces 45 of the holder are slightly bulged, as clearly shown in Fig. 2. This improves the appearance of the holder and also increases the protection to the watch provided by the holder. The holder is preferably perforated at a suitable point, as indicated at 23, for the attachment of a watch chain, cord or the like.

The term "leather" as used in the claims is intended to include other materials besides leather 50 which have leather-like qualities of flexibility and 55

resiliency. The term "annulus" is used in its broad sense to include holders that may have a non-circular outer periphery and even a non-circular inner periphery to fit upon a non-cylindrical watch case.

While I have described a preferred embodiment of my invention this is to be taken as illustrative and not limitative and I reserve the right to make various changes in form, construction and arrangements of parts without departing from the spirit and scope of my invention as pointed out in the claims.

I claim:

1. As an article of manufacture, a watch holder comprising an annulus of leather having an inner periphery adapted to fit upon a watch, the holder comprising a pair of lips along said inner periphery, said lips being resiliently flared apart.
2. As an article of manufacture, a watch holder comprising an annulus of leather having an inner periphery adapted to fit upon a watch, said annulus having a slit along the inner periphery thereof in a plane substantially parallel to a face of the annulus, and means wedged in the slit to flare apart the opposite walls of the slit.
3. As an article of manufacture, a watch holder comprising an annulus of leather having an inner periphery adapted to fit upon a watch, said annulus having a slit along the inner periphery thereof in a plane substantially parallel to a face of the annulus, and a cord wedged in the slit to flare apart the opposite walls of the slit.

4. As an article of manufacture, a watch holder comprising an annulus of leather having an inner periphery adapted to fit upon a watch, said annulus having a slit along the inner periphery thereof in a plane substantially parallel to a face of the annulus, and means wedged in the slit to flare apart the opposite walls of the slit, said annulus being also formed with a notch in its inner periphery to receive a watch crown.

5. As an article of manufacture, a watch holder comprising an annulus of leather having an inner periphery adapted to fit upon a watch, said annulus being formed of a pair of laminæ secured together at their outer periphery, and means urging the laminæ apart at their inner periphery. 10

6. As an article of manufacture, a watch holder comprising an annulus of leather having an inner periphery adapted to fit upon a watch, said annulus being formed of a pair of laminæ stitched together adjacent the outer periphery of the 20 holder, and a cord wedged between the laminæ and urging the laminæ apart at the inner periphery of the holder.

7. The combination with a watch having a cylindrical case with a flange at each end of the 25 cylinder, of an annular disk-like holder fitted upon the cylinder between the flanges, said holder being formed along its inner periphery with a pair of resilient lips, and means urging said lips apart against the flanges.

MAX E. WESTERMAN.
